UNITED STATES PATENT OFFICE.

ERASTUS WOODWARD, OF SOMERVILLE, ASSIGNOR TO GEORGE W. COPE-LAND, OF MALDEN, MASSACHUSETTS.

LASTING AND FASTENING MACHINE.

SPECIFICATION forming part of Letters Patent No. 248,544, dated October 18, 1881.

Application filed September, 19, 1881. (No model.)

To all whom it may concern:

Be it known that I, ERASTUS WOODWARD, of Somerville, in the county of Middlesex and State of Massachusetts, have invented a certain new and useful Improvement in Lasting and Tacking Machines, of which the following is a full, clear, and exact description, reference being had to the accompanying drawings, forming a part of this specification, in explaining its nature, in which—

Figure 1 is a front elevation of a machine embodying my invention. Fig. 2 is a plan of a portion of the jack-operative mechanism below the line $\alpha\alpha$ of Fig. 1. Fig. 3 is a side elevation thereof. Fig. 4 is a side elevation, enlarged, of a part of said mechanism, hereinafter referred to. Fig. 5 is a plan view of the entire machine. Fig. 6 is an enlarged view of a part of the jack-operative mechanism. Fig. 7 is a view, in elevation, of the jack and upper part of its operative mechanism turned a quarter to the right from the position shown in Fig. 1. Fig. 8 is a side elevation of the upper part of the machine. Figs. 9 and 10 are detail views.

This invention relates especially to mechanism for lasting the uppers of boots and shoes; but it may also be used for other purposes—such as the temporary tacking of an outsole to the insole after the lasting process, or the fastenings of stiffenings, welts, or counters to the insole—and for a great variety of other uses in which it is desirable to drive fastenings rapidly and with precision.

It embraces, first, the combination or organization in one machine of devices for driving fastenings having start and stop motions, and a jack for presenting the work to be operated upon to the driving devices, so constructed and operated in relation to each other that the placing in position of the work to receive the fastening will cause the fastening to be automatically driven or the machine to be automatically set in operation and automatically stopped; second, a jack of peculiar construction, whereby the inclination of the work to be operated upon is varied automatically, so that it always presents the proper inclination or position to the action of the fastening-driving mechanism; third, a jack and operative appliances adapted to be lifted by a foot-treadle in presenting the

work to the fastening-driving mechanism, and to fall rapidly to their original or lowest position by their own weight upon the release of the treadle; fourth, the combination and organization of a jack having an upward movement in relation to the fastening-driving devices, and a yielding guide of sufficient length to extend below the last when at its lowest level, so that it may serve to direct the upward movement of the jack to the nozzle of the fastening-driving device, as hereinafter explained; fifth, the organization, in a lasting-machine, of devices for driving fastenings, heel and toe lasting plates, or either, and a jack adapted to transfer the work from the fastening-driving device to said heel and toe lasting devices, or either, whereby the side portions of the upper may be lasted with the assistance of the fastening-driving device, and the work then moved without being taken from the jack to said lasting-plates.

In the drawings, A represents the standard or post of the machine. To the top of this standard is secured a machine, B, for driving fastenings; and the machine which I prefer to use contains the invention described in Patent No. 246,437, granted me August 30, 1881, or, in other words, has the start and stop motions therein specified.

The jack C may be of any suitable construction for holding the last at its heel and toe, and it and the adjusting mechanism, hereinafter spoken of, are supported by the rod c, which is hinged or pivoted at its lower end, c', to the arm or lever c², so that the rod c can be moved in any horizontal direction in relation to the post A. This hinge-connection, to be more specific, consists of the socket c³, supporting the rod c, and having downwardly-projecting lugs or ears c⁴, which straddle the plate or sleeve c⁵, to which they are fastened by the pivot c⁶. The plate c⁵ is adapted to swivel upon the pivot c⁶, projecting horizontally from the end of the lever c². This lever is pivoted at its inner end, c⁸, to a suitable support and has projecting from its side an arm, c⁹, which connects the lever c² with the treadle-lever c¹⁰. This connection is shown in Fig. 2. The treadle-lever is pivoted at c¹¹.

Between the rod c and the jack C there are two devices for adjusting the position of the

jack. The first or upper device, D, consists in appliances for changing the inclination of the last while it is being revolved in presenting the work to the fastening-driving appliances, 5 and the second, E, is a simple adjustment for varying the position of the jack in relation to the axis of the rod, and this last device comprises a plate, e, from the upper end of which projects upwardly the arm or plate e', and which has the curved slot e² near its lower end. This slotted plate is pivoted at e⁴ to the plate e⁵, which is fastened to the upper end of the rod e by a set-screw and socket, e⁶.

The plate e is locked in any desired position 5 in relation to the plate e⁵ by means of the screw-stud e⁷, which is fastened to the plate e⁵ and projects through the slot e² and the thumb-screw e⁸.

The device D, for automatically changing the inclination of the jack or the level of the surface of the insole, consists of the arm or plate e', above referred to, and the block d, upon which the jack rests, as shown in Fig. 6, and which is pivoted to the plate e' by the 15 pivot d'. This block d contains a shaft, d², which is fastened at its upper end, d³, to the lower part, d⁴, of the jack, and revolves therewith, and it carries the bevel-gear wheel d⁵, which meshes with the bevel-gear wheel d⁶.

This bevel-gear wheel d⁶ has a cylindrical extension or barrel, across the face of which is cut a long slot, d⁷. It has a bearing in the block d. In the slot d⁷ is a block, d⁸, arranged to be adjusted therein when desired, and from 25 which projects the stud or pin d⁹, which extends through the slot d¹⁰ in the upper part of the plate e'. This pin or stud plays up and down from the axial center of the gear d⁶ according as it is desired to throw or move the 30 block d in relation to the plate or arm e', and is in substance an adjustable crank-pin, by varying the position of which in relation to the said center of the bevel-gear the extent of movement of said block d is controlled and regulated.

The method of adjusting the stud or pin in the recess d⁷, and the manner of locking it in position by means of the thumb-screw d¹¹, may be effected as shown in Figs. 9 and 10; or the block d⁸ may be made in two parts and a projecting ledge on either side of the recess extended between them sufficiently to permit them to be clamped thereon by the stud or pin which passes from the inner plate, to which it is rigidly fastened through the outer block, 55 the sleeve, or roll which surrounds the stud and the thumb-screw d¹¹.

In order that the jack may not turn too easily upon the block d, I interpose the coiled spring f, surrounding the lower end of the shaft d², 50 between the nut f' and the lower surface of the block d, which acts to draw the jack to the block with stress enough to create sufficient friction for the purpose between the two parts. A bracket or support, G, through which the post c passes, and which is fastened to the standard A, holds the jack and its supporting mechanism in an upright position.

I have shown in the drawings plates for lasting the heel only; but it will be obvious from the following description that toe-lasting plates 70 can be used in lieu thereof, or that they can be arranged at the right hand of the standard and be used in connection with the heel-lasting plate. These heel-lasting plates are shown in Figs. 1 and 5 as attached to the end of the arm G', projecting laterally from the standard; but, of course, they may be supported by an independent frame, if desired. They are lettered g, are pivoted at g', have the arms g², which extend backward, and have projecting upwardly the 75 pins g³, which enter the curved slots g⁴ in the lever g⁵, which is pivoted at g⁶. It is obvious that the movement of the lever closes or opens the jaws or plates g according to the direction of its movement. These lasting-plates should 80 have such a location in relation to the fastening-driving device that the jack C can be moved from the one to the other, or, in case toe-lasting plates are used additionally to them, and if for any reason the surface of the insole should 85 become inclined from a horizontal position, or substantially a horizontal position, on account of this movement, the said plates may be operated on a corresponding level, instead of on a horizontal plane.

Of course I do not confine myself to the method of operating the lasting-plates shown, neither do I confine myself to hinged lasting-plates described; but I may use, in lieu thereof, any of the well-known constructions, and I name, 100 among others, those described in the various "Copeland" patents, so-called, the chief object of this portion of my invention being to arrange the lasting-plates, either toe or heel, or both, in such position in connection with the device 105 for driving fastenings that the work may be moved from the one to the other without being removed from its holding-jack. The upper, thus folded upon the surface of the heel or toe, or both, may be united to the insole in any desirable manner.

It will be observed that the machine for driving fastenings, instead of being provided with a foot or projection extending below the nozzle, through which the fastenings are driven, 115 described in said Patent No. 246,437, has what I consider an equivalent device in substance, (for which I am about to make a separate application,) a movable nozzle—that is, the lower end of the nozzle is vertically movable and 120 takes the place of the foot or projection of the said patent. In all other respects the intermediate connecting mechanism between the nozzle and the starting and stopping devices is substantially the same. It will therefore be 125 seen from this description that the act of placing the work in proper position for receiving the fastening starts the fastening-driving mechanism, drives the fastening, and stops the mechanism; and as the work is presented to the nozzle of the fastening-driving machine by means of a foot-treadle, it will also be observed that 130 the act of depressing the treadle not only places the work in proper position to receive the fast-

ening, but also causes the fastening-driving machine to be actuated.

Of course it is obvious that the connection between the treadle and jack and the fastening-driving machine, whereby the fastening may be driven upon the proper positioning of the work in relation to the nozzle to receive the fastening, may be somewhat different in construction from that above described and 10 yet be the equivalent therefor. This method of operating the machine would be produced if the treadle had, for instance, an independent arm or rod connecting it directly with the device for starting the machine, whereby, when 15 the work is placed in proper position, the machine shall be by that act of positioning put in operation; or the connection may be between the jack itself or any portion of its supporting mechanism and the actuating mechanism of the fastening-driving machine; or 20 an independent treadle and rod connecting it with the actuating device and fastening-driving machine can be used, the said treadle being so placed as to be operated by the foot at 25 the instant the work is properly placed in relation to the nozzle of the fastening-driving machine to receive the fastening; or a properly-located device to be moved by hand for thus 30 operating the fastening-driving machine might be employed.

In order that the work may be easily guided or directed or steadied while it is being lifted to the nozzle of the fastening-driving device, I have arranged back of the nozzle the guide H. 35 This guide is an improvement upon that described in the pending application of Jno. O. Bond, and differs from it in two features—first, in extending downwardly a sufficient distance to extend below the upper surface of the last 40 when it is at its lowest position, in order that in lifting the last it may not be moved under its lower end, but may be moved against it at once by a horizontal movement and may follow it from this lowest level to the nozzle; 45 second, in having an adjustment whereby the extent of its movement may be varied or limited. This device consists in the stud or block h and the screw h'. The spring h² passes between the inner surface of the head of the 50 screw and the outer surface of the stud, and of course the space between these two surfaces determines the extent of movement of the spring, and consequently the extent of movement of the guide. This guide, it is hardly 55 necessary to say, is a yielding one, and in that respect is like the guide described in said Bond application.

In the process of lasting the uppers of boots and shoes with the mechanism herein described, the upper is adjusted upon the last in the usual manner, and the last is mounted on the jack. The operator then seizes with pinchers or with his thumb and finger a proper section of the upper margin, which he draws 60 upon the surface of the insole while the last is in its lowest position. He then with his foot 65 lifts, by means of the foot-treadle and connect-

ing mechanism, the jack and last to the nozzle of the fastening-driving machine, and either while so doing or before, revolving the jack 70 so that the part of the upper to be tacked shall be immediately below the nozzle. With his hands he moves the jack horizontally toward the guide H either before he commences to lift it or while he is lifting it, and he steadies and 75 guides the work in its upward direction to the nozzle from that point thereby. The instant that the work is in position to receive the fastening the fastening is driven, or, in other words, the very act of properly locating the 80 work to receive the fastening causes the fastening to be driven.

Upon the driving of one fastening, if a wide section of the upper has been drawn over upon the insole, as before stated, the jack is lowered 85 a little by means of its own gravity and the partial release by the foot of the treadle, and is again raised to receive the second fastening, and so on until the section drawn over is properly secured, the foot in every instance governing 90 the lifting-and-falling movement of the jack. Upon the driving of the last fastening in the first section drawn over, the last and jack are dropped to their original position, another section of the edge of the upper is taken 95 hold of and folded upon the surface of the insole, the jack revolved to bring that section into line with the nozzle and is again lifted to the nozzle, and the operation of driving the fastenings, as above described, is continued. 100 This drawing over and folding of the edge upon the surface of the insole and fastening thereto may be continued until the entire upper is lasted, or it may be confined to the sides alone or to the sides and heel; and in this event 105 the toe or heel, or both, may be lasted by independent mechanism. In such case, after the lasting by this process is completed, the part to be finished, either toe or heel, or both, is brought in line with the folding-plates by the 110 movement of the jack, and is presented by the hand and by foot to said folding-plates, and the plates closed upon the surface of the insole, folding the edge of the upper thereon automatically. The edge thus folded is then fastened by means of hand-driven fastenings or by 115 power-driven fastenings, driven singly or in a group.

It will be noticed that the jack-adjusting devices are so contrived that the last is always 120 in the best position when under the nozzle to receive the fastenings, or, in other words, the last should be always so inclined in relation to the nozzle that the fastening shall be driven upon the line which, if extended, would pass 125 through the center, or very nearly the center, of the last, and the construction of jack-operating devices herein described automatically locates the last in this desirable position.

It is obvious that if the machine be run somewhat slowly the stop-motion, which is described as automatic, may be independently actuated.

For the purpose of working the fastening-

driving machine in the way intended it is only essential that there should be a tack-driving mechanism which, when the shoe is not presented to it for the reception of the tack, shall be at rest. This tack-driving mechanism, so normally at rest, must be thrown into revolution by the release of a catch, and the machine must be provided with a stop-motion which preferably is actuated automatically, as described.

The advantages of this invention consist, principally, in the speed and ease with which the lasting can be done.

Having thus fully described my invention, I claim and desire to secure by Letters Patent of the United States—

1. In an organized machine for lasting and tacking the uppers of boots and shoes, the combination of a jack and last adapted to be operated by a foot-treadle to present the work to the nozzle of an automatic fastening-driving device, and the automatic fastening-driving device whereby the last and jack are presented by the foot to the nozzle of the fastening-driving device, a tack or nail driven, and the jack and last automatically adapted to resume their original position upon the release of the treadle, substantially as described.

2. In an organized lasting and tacking machine, the combination of a jack for holding a last and presenting it to automatic fastening-driving mechanism, the said automatic fastening-driving mechanism, and an actuating device for starting the fastening-driving mechanism, constructed substantially as set forth, and adapted to be moved in the act of presenting the work in proper position for receiving the fastening, whereby the fastening may be driven at the instant that the work is so located, all substantially as and for the purposes described.

3. In an organized machine for lasting and tacking the uppers of boots and shoes, the combination of a jack for holding and presenting the last to an automatic fastening-driving device, the automatic fastening-driving device, and the means for setting said fastening-driving device in operation, arranged or located to be automatically moved upon the placing in position of the last, whereby a fastening is driven at the instant the last is so located, all substantially as and for the purposes described.

4. In an organized machine for lasting and tacking the uppers of boots and shoes, the combination of a jack for holding and presenting the last to an automatic fastening-driving device, the automatic fastening-driving device, and the means for starting and stopping its operation, adapted to be operated or moved automatically upon the placing in proper position of the last or work in relation to the nozzle, whereby upon the instant said work is

so located a fastening is driven and the machine automatically stopped, all substantially as and for the purposes described.

5. In an organized machine for lasting the uppers of boots and shoes, the combination of a jack for holding and supporting the last and for presenting it and the work thereon to an automatic fastening-driving device, said fastening-driving device, means for stopping it, and an unweighted foot-treadle for operating the jack, all arranged so that as the jack is lifted the stop-motion mechanism is operated, all substantially as and for the purposes described.

6. In an organized lasting-machine, the combination of a jack for holding the last and presenting it and the work thereon to an automatic fastening-driving device, means for moving the same horizontally and vertically in relation thereto, and a yielding guide, H, of a length sufficient to extend below the lowest level of the upper portion of the last, all substantially as and for the purposes described.

7. In an organized machine for lasting the uppers of boots and shoes, the combination of an automatic device for driving fastenings, the lasting-plates, a jack for holding a last and the work thereon, and the means whereby the jack may be moved from one device to the other, all substantially as and for the purposes described.

8. The combination of the jack C and means, substantially as specified, for automatically changing its inclination or level as it is revolved, consisting of the pivoted block d, the shaft d³, and bevel-gear d⁵ d⁶, the crank-pin d⁹, and the plate e', having the slot d¹⁰, all substantially as and for the purposes specified.

9. In a lasting and tacking machine, the means for adjusting the extent of inclination of the jack, consisting of the gear d⁶, recessed as specified, a crank-pin adjustable in said recess, and the plate e', having a slot in which the crank-pin plays, all substantially as set forth.

10. The combination of the block d, the jack C, means for securing the jack to the block in a manner to enable the same to be revolved thereon, and friction devices for creating friction between the block and jack, all substantially as and for the purposes described.

11. The combination of a jack, its supporting-rod e, and means for adjusting the inclination of the jack in relation to the rod, consisting of the plate e, a plate, e', pivoted at e⁴ to the plate e, and having the slot e² and the locking device e⁷ e⁸, all substantially as described.

ERASTUS WOODWARD.
